US00D788071S

(12) **United States Design Patent** (10) **Patent No.:** **US D788,071 S**
(45) **Date of Patent:** **** May 30, 2017**

(54) **GAMING HEADSET**

(71) Applicant: **Voyetra Turtle Beach, Inc.**, Valhalla, NY (US)

(72) Inventor: **Andrew Logan**, Calabasas, CA (US)

(73) Assignee: **VOYETRA TURTLE BEACH, INC.**, Valhalla, NY (US)

(**) Term: **15 Years**

(21) Appl. No.: **29/549,107**

(22) Filed: **Dec. 18, 2015**

Related U.S. Application Data

(63) Continuation of application No. 29/529,087, filed on Jun. 3, 2015, now Pat. No. Des. 745,860.

(51) **LOC (10) Cl.** **14-01**

(52) **U.S. Cl.**

USPC **D14/205**

(58) **Field of Classification Search**

USPC D14/205, 206, 188, 192, 372, 496; 345/7, 8; D29/112; 2/209; 181/129, 181/130, 135; 379/430, 431; 381/380, 381/381

CPC H04R 1/1066; H04R 1/10; H04R 25/00; G09G 5/00

See application file for complete search history.

(57) **CLAIM**

The ornamental design for a gaming headset, as shown and described.

DESCRIPTION

FIG. 1 is a front perspective view of a gaming headset showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a rear perspective view thereof.

The dashed broken lines illustrate portions of the gaming headset that form no part of the claimed design.

The wavy black line at the end of the cable represents an unclaimed boundary line and forms no part of the claimed design.

1 Claim, 8 Drawing Sheets
